UNITED STATES PATENT OFFICE

NORMAN L. SNOW, OF NEW CANAAN, CONNECTICUT, ASSIGNOR TO DIAMOND POWER
SPECIALTY CORPORATION, OF DETROIT, MICHIGAN, A CORPORATION OF MICHIGAN

BOILER CLEANER

Application filed May 4, 1925, Serial No. 27,976. Renewed November 18, 1930.

The invention relates to boiler cleaners and refers more particularly to a boiler cleaner adapted for use in connection with a locomotive power plant. One of the objects of the invention is to provide means for automatically operating the boiler cleaner after the locomotive has travelled a predetermined distance. A further object is to provide means whereby the boiler cleaner is operatively connected with a moving part of the locomotive whereby the latter furnishes the necessary power to actuate the boiler cleaner. A further feature resides in the provision of valve-controlled means for automatically shutting off the supply of cleaning fluid after the boiler cleaner has operated a predetermined time.

Referring to the drawings:

Figure 17 is a view corresponding to Figure 2 showing the manner of operating the 60 boiler cleaner shown in Figure 15; and

Figure 18 is a semi-diagrammatic view showing the piping system for supplying the cleaning fluid to the blower elements.

Referring to the drawings in which like 65 reference characters indicate like parts, reference character A represents the cab end of a locomotive, B indicating the cab. The locomotive may be provided with firebox C, flue sheet D, boiler tubes E, and driver or trailer 70 F, all of which parts may be of usual or other preferred construction. G indicates a boiler cleaner which may be of the blower type installed through one of the locomotive side wall water legs H and nipple 10. The blower G 75 may be mounted on suitable brackets 11 or supported in any other suitable manner.

In order that cleaning fluid may be automatically supplied to the blower after a predetermined distance has been travelled by the 80 locomotive the following mechanism is provided;

K indicates a gear box which may be supported by suitable brackets 12 secured to the side of the locomotive, the gear box K housing a train of reduction gearing L, the driving end of which is provided with a shaft 12' having an end projecting away from the side of the boiler water leg and journaled in a bearing 13 of the depending bracket 14. The 85 lower end of bracket 14 journals a shaft 15 adapted to be rotated by a pulley or the like 16, which is keyed to shaft 15. For supplying power to rotate the pulley 16 I may connect the pulley to any moving part of the locomotive. One manner of so driving the pulley is shown in Figure 1. 17 indicates the shaft upon which is mounted the trailer F. Located upon the shaft 17 is a driving pulley 18, the shaft 17 preferably being extended 90 100

outwardly for receiving the pulley 18. Power from the trailer is communicated to the shaft 15 by reason of a belt 19 or the like for transferring rotative movement from pulley 13 to pulley 16. M represents a mechanism for causing shaft 12' to always rotate in a given direction regardless of whether the locomotive is travelling forward or backward. Such a provision, while not necessary, is desirable in causing efficient operation of the blower. Referring to Figures 4, 5, and 6 the mechanism M comprises the following parts. N and O indicate clutches, the clutch N having a hub part 20 fixed to shaft 15; the hub 20 is provided with the wedge faces 21 within the annular flange 22 of pulley 23, the latter being loosely mounted on shaft 15. Between the faces 21 and the flange 22 the rolls 24 operate to cause driving engagement between shaft 15 and pulley 23 when shaft 15 is rotated in one direction, clockwise as shown in Figure 6 as will be readily understood. A like construction is embodied in clutch O except that the latter clutch is arranged with its wedge faces arranged oppositely with those of the clutch N whereby, when shaft 15 rotates counterclockwise as viewed in Figure 6, clutch N will be disengaged and clutch O will be engaged to establish a drive between shaft 15 and pulley 25. Loosely mounted on shaft 12' are pulleys 26 and 27, the former having driven connection with pulley 23 by an open belt 28 and the pulley 27 being driven from pulley 25 by a crossed belt 29. Pulley 26 carries a pawl 30 normally urged inwardly to engage the teeth 31 of ratchet 32 fixed to shaft 12'. Pulley 27 is likewise provided with a pawl and ratchet mechanism whereby when one of the pulleys 26 or 27 is being driven from shaft 15 to rotate shaft 12' through the pawl and ratchet mechanism, the other of said pulleys will remain idle, the idle pawl permitting rotation of the shaft 12'. From the foregoing mechanism it will be apparent that regardless of the movement of the locomotive forwardly or in reversing the shaft 12' will be caused to rotate always in a given direction.

The opposite end of the gear train L is provided with a rotatable cam disk 33 provided with a cam face 34 adapted to engage valve stem 35 to unseat valve 36 against the action of a spring 37 normally keeping valve 36 against its seat 38. 39 indicates a pipe for conducting a supply of cleaning fluid such as steam, air, or the like, to the line 40 and thence to the blower G. 41 indicates a drain line which may or may not be automatic in its operation. 42 indicates a bypass from supply pipe 39 and communicates with the chamber 43. Cleaning fluid from chamber 43 is adapted to pass through port 44 when valve 36 is unseated by the cam 34, and thence pass through chamber 45. 46 is a pipe line leading from chamber 45 to the

cylinder 47 where the cleaning fluid acts on a piston 48 to unseat valve 49 to permit cleaning fluid to pass from supply pipe 39 to the line 40. P indicates a slow-acting device for automatically shutting-off the supply of cleaning fluid to the cylinder 47 after a predetermined time has elapsed after the unseating of valve 36. Referring to Figure 9A the device P consists of a valve 50 controlling the passage of cleaning fluid in pipe 46, the valve 50 being normally held raised from its seat by the pressure of cleaning fluid in pipe 46 acting against the valve to urge the same upwardly against the action of spring 51 thus allowing cleaning fluid to pass to the cylinder 47. 52 is a valve stem carrying piston 53 at its upper end, the piston operating in cylinder 54. 55 is a by-pass from pipe 46 to the upper end of cylinder 54, the rate of flow of the cleaning fluid from the by-pass 55 into the cylinder being controlled by an adjustable needle valve 56. 57 is a supporting bracket for supporting the cylinder in operation of this part of the device. After the cam 34 has acted to unseat valve 36, cleaning fluid will be supplied from pipe 39 and 42 to the chamber 45 and thence to pipe 46. Cleaning fluid from pipe 46 acts to unseat valve 50 and thence enters chamber 47 where it acts on piston 48 to unseat the valve 49 and thus supply cleaning fluid to the blower G. Cleaning fluid will also enter the by-pass 55 and will enter cylinder 54 building up a pressure therein. The rate at which such pressure is built up in cylinder 54 is determinable by the needle valve 56. When the pressure in cylinder 54 is sufficient the piston 53 aided by the action of spring 51 will be moved to seat valve 50 and thus shut off the supply of cleaning fluid to chamber 47 whereby the valve 49 will seat, shutting off the supply of cleaning fluid to the blower.

For controlling the valve 49 independently of the distance traveled by the locomotive I may provide the by-pass pipe 57' extending from pipe 39 to a point convenient for control as within the cab B as indicated at B' in Figure 1. Thus a control valve 58 may be provided whereby at any time desired cleaning fluid may be conducted from pipe 57' through pipe 59 to unseat valve 49 and cause the blower G to function.

In order to impart movement to the blower G from the reduction gear train L only when cleaning fluid is being supplied to the blower the mechanism shown in Figure 8 is provided. 60 indicates one of the cross shafts of the reduction gearing, the shaft 60 being axially movable and having an extension 61 passing through cylinder 62 supported by bracket 63. 64 and 65 indicate gears of reduction gearing L, these gears being splined with the shaft 60 by reason of the key 66 extending longitudinally of the shaft 60. 70 represents collars adapted to

maintain the proper relative position of the gears 64 and 65 within the gear box K. 71 is a pulley loosely mounted on the shaft extension 61, the pulley 71 having a clutch member 72 adapted to be engaged by the complementary clutch member 73, the latter being fixed with shaft 61. 74 represents a piston fixed with shaft 61 and operable within the cylinder 62. The shaft 61 and parts fixed therewith are urged outwardly from the boiler water leg by springs 75 and 76 causing disengagement of the clutch faces 72 and 73. 77 is a pipe communicating with the supply line 40. Thrust bearings 78 may be provided for taking up the thrust in the opposite movements of shaft 60 in operation of those parts of the device. Whenever cam 34 is disengaged from valve stem 35 or whenever cleaning fluid is not being directed to the blower G, the pipe 77 will be free of cleaning fluid thus permitting springs 75 and 76 to move the shaft 60 to the left or to the position shown in Figure 8. In such position, movement of the locomotive and hence reduction gearing L will not serve to rotate the pulley 71 until cleaning fluid is being supplied to the blower through pipe 40; at such time cleaning fluid will enter cylinder 62 to act on the piston 74 whereby the shaft is moved to the right engaging the clutch faces 72 and 73 to establish a driving connection from the reduction gearing to the pulley 71.

Pulley 71 is connected through a belt 78' with a pulley 79 rotatably supported adjacent the blower G by a bracket 80. 81 indicates a pin extending outwardly from the face of pulley 79 for reciprocating the blower nozzle referred to hereinafter. 82 indicates a yoke having a slot 83 within which the pin 81 acts. It will be noted that as the pulley 79 is rotated the pin 81 will reciprocate the yoke 82 and consequently the shaft 84, which is fixed with the upper end of the yoke. 84 indicates a bearing bracket for the shaft 84. Shaft 84 carries a bevelled gear 84a meshing with a gear 84b fixed to a shaft 84c which enters the side of the blower housing.

It is desirable to locate a blower in each of the side water walls of the boiler, each blower being adapted to direct cleaning fluid over substantially half of the flue sheet. However, a single blower could be used if preferred having a capacity for cleaning the whole flue sheet. Further if desired the control mechanism such as shown in Figure 1 could readily be adapted to control and operate a blower in each of the side wall water legs. I prefer however to provide such a mechanism as shown in Figure 1 on each side of the locomotive for controlling each of the blowers.

In detail the construction and operation of one of the blowers G may be as follows:

Located in each side of the water leg H is

a blower G preferably of the type normally housed within the water leg protected from the heat of the firebox but automatically projected forwardly into the firebox under the action of the cleaning fluid. Such a blower is shown in Figures 10 to 14. In general this type of blower is provided with a discharge nozzle which upon being projected forwardly into the firebox under the influence of the cleaning fluid, is directed to discharge the cleaning fluid against the boiler tube sheet for cleaning the same together with the boiler tubes and associated parts of the boiler which accumulate soot, dirt, and the like. The nozzle may be formed with one or more discharge orifices. In its projected position the nozzle of the blower is adapted to be rocked or oscillated in order to cause the jet of cleaning fluid to sweep over the tube sheet.

These blowers are located a suitable distance back of the tube sheet D with their nozzles 89 directed toward the tube sheet. The blower is connected to the cleaning fluid supply line 40. When the cleaning fluid is supplied to the blower the cleaning fluid passes through the line 40 and into the chamber 85 whence it acts on the plunger 86 and forces the same forward, carrying with it plunger tube 87 and compressing the spring I₁ until the thrust bearing I₂ is brought into contact with the spacer I₃, the outer face of the thrust bearing bearing against the segmental gear 88.

The forward end of the spacer I₃ bears against the packing housing I₄ which is rigidly secured to sleeve I₅. The sleeve I₅ is rigidly carried by the blower housing as at I₆. As the plunger 86 goes forward under the action of the cleaning fluid the nozzle is forced inside of the inner wall of the water leg as shown in Figure 11 and the jet of cleaning fluid from the nozzle 89 is directed against the tube sheet. It will be noted that the entire stream is concentrated through a single nozzle so that the cleaning fluid is played with greater force against a relatively small area of the tube sheet upon reciprocation of the shaft 84 within the limits set by the rod J₂ fixed to the housing and extending through the slot J₄ on the lower part of the segmental gear 88. The plunger tube 87 will turn the plunger 86 and the nozzle 89 through an arc of approximately 90° covering the boiler tubes in direct line with the nozzle either vertically the full height of the tube sheet, or if desired the nozzle could be arranged to discharge in a horizontal line. The segmental gear 88 is fixed, by a set screw J₆, on the plunger tube 87. Between plunger 86 and plunger tube 87, is located a spider H₂, secured to tube 87 by set screws H₃ which have inwardly extending fingers H₄ engageable in the circumferential groove H₅ of the rod J' so as to prevent relative longitudinal movement between rod J' and the tube 87, but to permit relative ro-

tation of these parts. H_6 are other set screws, for securing plunger 86 with the spider H_2 , the set screws H_6 also serving to lock the set screws H_3 in place. As shown in Fig. 13, the 5 cleaning fluid is free to pass spider H_2 in traveling longitudinally in plunger 86.

The gear K_2 fixedly mounted on the rod J' as by a key H_7 acting through the pinion 90 and the gear 91 cut in the base of the nozzle 89 is carried forward by the ratchet 92 as long as the segmental gear is turning to the left. When the motion of the shaft 84 is reversed the gear K_2 is held against free movement by a ratchet M' pivotally mounted on the 10 housing M_2 frictionally mounted on the shaft J' and likewise provided with a slot J_5 . The result of this is that the gear K_2 initially moves with the housing M_2 until the housing M_2 is prevented from further movement by 15 the rod J_2 in slot J_5 . The gear K_2 is then held stationary so that continued movement of the gear 88 moves plunger 87 relative to the shaft J' to vary the angle of nozzle 89. The amount 20 of this motion is limited by the ratio between the pinion 90 and the gear 91 and by the adjustment of the set screw 93 extending into slot J_5 and threaded in the opening N' at the lower end of the housing M_2 . This allows 25 movement of the housing M_2 with relation to the rod J' . As the oscillatory movement of 30 shaft 84 continues it will be seen that an intermittent circular movement is transmitted to the nozzle 89 and that this motion changes the relation of the axis of the nozzle 89 to 35 that of the plunger 86, resulting in a changed direction of the cleaning fluid jet from the nozzle 89.

In operation before the cleaning fluid is supplied to line 40 the spring I' will hold the 40 parts in the position shown in Figure 10, the nozzle being housed within the water leg of the boiler. When the cleaning fluid is admitted to the blower through pipe 40 the nozzle 89 restricts the flow of cleaning fluid 45 sufficiently so that the plunger 86 will be projected forwardly carrying with it plunger tube 87 and rod J' so that the segmental gear 88 will be carried forwardly on the plunger tube 87 to mesh with the bevelled 50 gear 94 driven by the shaft 84c, and the thrust bearing I_2 will take up the thrust through the spacer I_3 and sleeve I_5 . The parts are 55 now ready for operation by the shaft 84. As the shaft 84 is rotated by the yoke 82 to move the segmental gear 88 to the left or counter-clockwise as shown in Figure 14 pawl 92 will rotate gear K_2 until the end of slot J_4 contacts with rod J_2 to prevent further operation 60 of segmental gear 88. During this rotation the housing M_2 which is frictionally carried on shaft J' also swings counterclockwise by reason of its slot J_5 . Thus it will be seen that plunger 86 will have been rocked with nozzle 89 without relative movement 65 therebetween, the nozzle 89 throwing its jet

of steam in a vertical path for the height of tube sheet.

When the shaft 84c is rocked in the opposite direction to rotate segmental gear 88 to the right or clockwise as shown in Figure 14, 7 rod J' , housing M_2 frictionally mounted thereon, gear K_2 and segmental gear 88 will all rotate together until further rotation of the housing M_2 is prevented by reason of set screw 93 contacting with the rod J_2 . For the 75 remaining movement of the segmental gear 88 the housing M_2 will act through pawl M' to prevent further rotation of the gear K_2 and rod J' so that during this remaining movement the plunger tube 87 will be rotated with respect to the rod J' thus acting through bevelled gears 90 and 91 to advance the direction of nozzle 89. By regulating the set screw 93 the increment of advance of the nozzle may be varied. The parts are then in position for 80 the next cycle which will include first tracing a vertical path by the blower jet down the tube sheet substantially parallel with the preceding and spaced therefrom a distance determined by the relative movement between 85 the gears 90 and 91.

The proper length of travel back and forth of segmental gear 88 may be readily obtained by the ratio of the gears 84a and 84b; also the structure of the yoke 82, and the size of pulley 90 79.

It will be apparent from the foregoing that I have provided means for automatically cleaning the locomotive flue sheet and boiler tubes after a predetermined distance 100 has been travelled by the locomotive. By reason of the reduction gears and the pulleys shown the period between the blowing operations may be made to correspond with any desired distance of travel of the locomotive. 105 It will further be noted that the locomotive supplies the power from a moving part thereof for operating or reciprocating the blower. It will further be noted that I have provided means for shutting off the supply 110 of cleaning fluid to the blower after a predetermined elapse of time after the cam 34 has unseated the valve 36. If desired the face of the cam may be varied to further regulate the time of contact with the valve stem 115 35 to thus vary the period of supply of cleaning fluid to the blower. Such period may be further regulated by the ratio of the various gears comprising the reduction gearing L. I have furthermore provided means for 120 manually controlling the operation of the blower independently of the distance travelled by the locomotive.

Instead of providing a reciprocating, reTRACTING, and projecting type of blower as 125 shown in Figures 10 to 14 I may provide other types of blowers, for example in Figures 15, 16, and 17, I have shown a non-retracting type of blower adapted to be rotated by power derived from a moving part 130

of the locomotive. In these figures the blower G' is provided with a rotatable portion R formed with the radial walls 95 to provide a plurality of cleaning fluid conducting passages 96. The forward end of each of these passages terminates in a nozzle 97, the axes of the nozzles being relatively different whereby, as the portion R is rotated the nozzles will be successively directed toward different portions of the flue sheet, cleaning fluid issuing from the nozzles during the time that they are thus directed toward the flue sheet. Since the axis of each successive nozzle differs in predetermined amount from the axes of the other nozzles it will be apparent that each nozzle will trace a vertical line for the height of the flue sheet, the successive lines traced being parallel and relatively spaced whereby the desired portion of the tube sheet may be cleaned by a nozzle.

In order to limit the passage of the cleaning fluid to such of the nozzles as are directed toward the flue sheet, a port 98 is provided which successively communicates with the desired passages 96 by reason of the passage ports 99.

For rotating the blower the body R is provided at its rear with a shaft 100 upon which is fixedly mounted a pulley 101 adapted to be rotated by the actuating belt 78' from the reduction gearing L as aforesaid.

What I claim as my invention is:

1. In a locomotive, the combination with a moving part thereof, of a boiler cleaner movable for cleaning parts of the boiler, and a driving connection between said moving part and said boiler cleaner for moving the latter from the former.

2. In a locomotive, the combination with a moving part thereof, of a blower movable for cleaning parts of the boiler, and means for applying power from said moving part of the locomotive to the blower for moving said blower.

3. In a locomotive, the combination with a moving part thereof, of a blower movable for cleaning parts of the boiler, and means for applying power from said moving part of the locomotive to the blower for periodically moving said blower.

4. In combination with a locomotive provided with a ground wheel, a boiler cleaner, and a geared connection between the ground wheel and boiler cleaner whereby power is transmitted from the ground wheel to the boiler cleaner for operating the boiler cleaner.

5. In combination with a locomotive, a blower having a discharge nozzle adapted to be moved for cleaning parts of the boiler, and means for applying power from a movable part of said locomotive to said blower for moving said nozzle.

6. In combination with a locomotive, a blower having a discharge nozzle adapted to be moved for cleaning parts of the boiler,

and means for applying power from a movable part of said locomotive to said blower for periodically and automatically moving said nozzle.

7. In combination with a locomotive, a blower having a discharge nozzle adapted to be moved for directing a jet of cleaning fluid against parts of the locomotive boiler to be cleaned, and means for automatically applying power at predetermined intervals from a moving part of said locomotive to said blower nozzle for moving said nozzle.

8. In combination with a locomotive, a blower having a discharge nozzle adapted to be moved for directing a jet of cleaning fluid against parts of the locomotive boiler to be cleaned, and means for automatically applying power at predetermined intervals from a moving part of said locomotive, to said blower nozzle for moving said nozzle, said intervals being dependent on the distance travelled by the locomotive.

9. In combination with a locomotive, a blower having a discharge nozzle adapted to be moved for directing a jet of cleaning fluid against parts of the locomotive boiler to be cleaned, means for automatically applying power at predetermined intervals from a moving part of said locomotive to said blower nozzle for moving said nozzle, and means for automatically applying cleaning fluid to said blower at the times when the said nozzle is being moved.

10. In combination with a locomotive, a blower having a discharge nozzle adapted to be moved for directing a jet of cleaning fluid against parts of the locomotive boiler to be cleaned, reduction gearing, and means for applying power from a moving part of the locomotive through the reduction gearing for moving said nozzle.

11. In combination with a locomotive, a blower having a discharge nozzle adapted to be moved for directing a jet of cleaning fluid against parts of the locomotive boiler to be cleaned, reduction gearing, and means for applying power from a moving part of the locomotive through the reduction gearing for moving said nozzle, said means automatically acting after the locomotive has travelled a predetermined distance.

12. In combination with a locomotive, a blower having a discharge nozzle, a rotatable element, means connecting the said element and nozzle for moving the nozzle, and a mechanism for transmitting power from a moving part of the locomotive to said rotatable element for rotating the same.

13. In combination with a locomotive, a blower having a discharge nozzle, a rotatable element, means connecting the said element and nozzle for moving the nozzle, and a mechanism for transmitting power from a moving part of the locomotive to said rotatable element for rotating the same, said mecha-

nism adapted to rotate said element in the same direction for movements of the locomotive, either forward or in reverse.

14. In combination with a locomotive, a blower having a movable discharge nozzle for directing a jet of cleaning fluid against parts of the boiler to be cleaned, a cleaning fluid supply pipe for conducting cleaning fluid to said blower, a valve for controlling the passage of cleaning fluid from said pipe to said blower, means for automatically unseating said valve after the locomotive has travelled a predetermined distance, and means for supplying power from a movable part of the locomotive for moving said nozzle at the times when the cleaning fluid is being supplied to said blower.

15. In combination with a locomotive, a blower having a movable discharge nozzle for directing a jet of cleaning fluid against parts of the boiler to be cleaned, a cleaning fluid supply pipe for conducting cleaning fluid to said blower, a valve for controlling the passage of cleaning fluid from said pipe to said blower, means for automatically unseating said valve after the locomotive has travelled a predetermined distance, means for shutting off the delivery of cleaning fluid to said blower after a predetermined interval from the time of initial supply, and means for supplying power from a movable part of the locomotive for moving said nozzle at the times when the cleaning fluid is being supplied to said blower.

16. In combination with a locomotive, a blower having a movable discharge nozzle for directing a jet of cleaning fluid against parts of the boiler to be cleaned, a cleaning fluid supply pipe for conducting cleaning fluid to said blower, a valve for controlling the passage of cleaning fluid from said pipe to said blower, means for automatically unseating said valve after the locomotive has travelled a predetermined distance, a slow-acting device for automatically shutting off the supply of cleaning fluid to the blower after a predetermined time has elapsed after the unseating of said valve, and means for supplying power from a movable part of the locomotive for moving said nozzle at the times when the cleaning fluid is being supplied to said blower.

17. In combination with a locomotive, a blower having a movable discharge nozzle for directing a jet of cleaning fluid against parts of the boiler to be cleaned, a cleaning fluid supply pipe for conducting cleaning fluid to said blower, a valve for controlling the passage of cleaning fluid from said pipe to said blower, means for automatically unseating said valve after the locomotive has travelled a predetermined distance, and means for supplying power from a movable part of the locomotive for moving said nozzle at the times when the cleaning fluid is being supplied to said blower.

plied to said blower, and manually controlled means for unseating said valve independently of the said automatic means.

18. In combination with a locomotive, a blower having a movable discharge nozzle for directing a jet of cleaning fluid against parts of the boiler to be cleaned, a cleaning fluid supply pipe for conducting cleaning fluid to said blower, reduction gearing, means for transmitting power from a moving part of the locomotive to said reduction gearing, means controlled by the reduction gearing for controlling the supply of cleaning fluid through said supply pipe, means connected with the reduction gearing for moving said nozzle, said last named means including a clutch, and means dependent upon the supply of cleaning fluid to said blower for operating said clutch.

19. In combination with a locomotive, a blower having a movable discharge nozzle for directing a jet of cleaning fluid against parts of the boiler to be cleaned, a cleaning fluid supply pipe for conducting cleaning fluid to said blower, reduction gearing, means for transmitting power from a moving part of the locomotive to said reduction gearing, means controlled by the reduction gearing for controlling the supply of cleaning fluid through said supply pipe, means connected with the reduction gearing for moving said nozzle, said last named means including a clutch, and cleaning fluid operated means dependent upon the supply of cleaning fluid to said blower for operating said clutch.

20. In combination with a locomotive, a blower having a movable discharge nozzle for directing a jet of cleaning fluid against parts of the boiler to be cleaned, a cleaning fluid supply pipe for conducting cleaning fluid to said blower, reduction gearing, means for transmitting power from a moving part of the locomotive to said reduction gearing, a valve for controlling the passage of cleaning fluid from said pipe to said blower, a valve stem, a cam movable by said reduction gearing for periodically acting on said valve stem to unseat said valve, driving means connected with the said reduction gearing for moving the nozzle, a cleaning fluid operated clutch, and means for establishing a driving connection through said clutch when cleaning fluid is being delivered to said blower whereby said nozzle is moved through the driving means aforesaid.

21. In combination with a locomotive, a blower having a movable nozzle adapted to discharge cleaning fluid against parts of the locomotive boiler to be cleaned, and means automatically acting after the locomotive has travelled a predetermined distance forwardly or in reverse for supplying power from a moving part of the locomotive to move said nozzle.

22. In combination with a locomotive hav-

- ing a side wall water leg, a blower housed within said water leg and provided with a nozzle adapted to be projected into the firebox of the locomotive for cleaning parts of the boiler, a source of cleaning fluid, means for transmitting power from a moving part of the locomotive to move said nozzle in its projected position, and means for automatically periodically acting to conduct cleaning fluid from said source to said blower for projecting the blower nozzle and causing a discharge of cleaning fluid from said nozzle. 23. In combination with a locomotive having a side wall water leg, a blower housed within said water leg and provided with a nozzle adapted to be projected into the firebox of the locomotive for cleaning parts of the boiler, a source of cleaning fluid, means controlled by the distance travelled by the locomotive for supplying cleaning fluid from said source to said blower nozzle, and for transmitting power from a moving part of the locomotive to said nozzle for moving the nozzle during the discharge of cleaning fluid therefrom. 24. In combination with a locomotive having a side wall water leg, a blower housed within said water leg and provided with a nozzle adapted to be reciprocated for directing the nozzle toward parts of the boiler to be cleaned, a source of cleaning fluid for supplying cleaning fluid to said nozzle, and means for transmitting power from a moving part of the locomotive to reciprocate said nozzle. 25. In combination with a locomotive having a side wall water leg, a blower housed within said water leg, and having a nozzle adapted to be rotated to discharge a jet of cleaning fluid adjacent parts of the boiler to be cleaned, a source of cleaning fluid, and means for transmitting power from a moving part of the locomotive to rotate said blower nozzle. 26. In combination with a locomotive having a side wall water leg, a blower housed within said water leg and having a nozzle adapted to be rotated to discharge a jet of cleaning fluid adjacent parts of the boiler to be cleaned, a source of cleaning fluid, means for transmitting power from a moving part of the locomotive to rotate said blower nozzle, and means for automatically periodically acting to conduct cleaning fluid from said supply to said blower nozzle. 27. In combination with a locomotive having a side wall water leg, a blower housed within said water leg and having a nozzle adapted to be rotated to discharge a jet of cleaning fluid adjacent parts of the boiler to be cleaned, a source of cleaning fluid, means controlled by the distance travelled by the locomotive for supplying cleaning fluid from said source to the blower, and transmitting power from a moving part of the locomotive to rotate said blower nozzle. 28. In a locomotive, the combination with a moving part thereof, of a rotatable blower element for cleaning parts of the boiler, and a driving connection between said moving part and said blower element for rotating the latter from the former. 29. In a locomotive, the combination with a moving part thereof, of a movable blower element for cleaning parts of the boiler, and means for transmitting power from the said moving part of the locomotive to said blower element for moving the same, said means being operable to always move said blower element in the same direction irrespective of the direction of movement of the said moving part of the locomotive. 30. In combination with a locomotive, a movable blower element for directing jets of cleaning fluid adjacent parts of the boiler to be cleaned, a valve for controlling the passage of cleaning fluid to said blower element, manually controlled means for unseating said valve, and means for supplying power from a movable part of the locomotive for moving said blower element. 31. In a device of the character described, a blower element, a main valve for controlling the flow of cleaning fluid to said blower element; fluid pressure actuated means for actuating said main valve, an auxiliary valve for controlling the flow of cleaning fluid to said pressure actuated means, means for periodically automatically opening said auxiliary valve, and means automatically operable to cut off the supply of fluid under pressure to said pressure actuated means a predetermined time after the opening of said auxiliary valve. 32. In a device of the character described, a blower element, a main valve for controlling the flow of cleaning fluid to said blower element, a piston connected to said main valve for actuating the latter, an auxiliary valve for controlling the flow of cleaning fluid to said piston, and means automatically operable to cut off the supply of cleaning fluid to said piston a predetermined time after the opening of said auxiliary valve. 33. In combination with a locomotive, a blower element, a main valve for controlling the flow of cleaning fluid to said blower element, an auxiliary valve adapted when open to effect an opening of said main valve, means for periodically opening said auxiliary valve in dependence upon the distance traveled by the locomotive, and means automatically operable to effect a closing of said main valve a predetermined time after the opening of said auxiliary valve. In testimony whereof I affix my signature.
NORMAN L. SNOW.
